UNITED STATES PATENT OFFICE

MARIUS LATOUR, OF NEW YORK, N. Y., ASSIGNOR TO LATOUR CORPORATION, OF JERSEY CITY, NEW JERSEY, A CORPORATION OF DELAWARE

ELECTRIC SIGNALING

Application filed March 9, 1925. Serial No. 14,221.

One of the principal objects of my invention is the provision of simple and effective means for preventing the establishment of undesirable oscillations in signaling systems.

Another object of my invention is the provision of simple, cheap and effective coupling means between various devices in signaling systems, said coupling means also improving the degree and quality of amplification.

Other objects and advantages of my invention will be apparent from the following description taken in conjunction with the accompanying drawing.

Referring to the drawing which is a schematic diagram of a preferred embodiment of my invention, the control-electrode cathode circuit of thermionic tube or relay 1 is coupled to the source of signal waves by means of the coupling device 2. The coupling device 2 comprises a primary and a secondary coil inductively related to each other as shown. The primary coil is connected across the source of signal waves and has a variable condenser 3 connected across its terminals for tuning to the desired frequency.

The control electrode-cathode circuit of relay 1 comprises an inductance 4 and the secondary winding of coupling device 2 connected in series with each other and arranged in the circuit as shown. A condenser 5 is connected across the secondary winding for tuning the circuit to the desired frequency. The inductance 4 preferably possesses a magnetic circuit comprising magnetic material whereby the impedance of the inductance increases materially as the signal frequency increases. This is desirable in view of the fact that the higher the frequency the greater the tendency is to the establishment of undesirable oscillations, and therefore the desirability of a greater impedance in the grid circuit for preventing the establishment of these oscillations.

The anode-cathode circuit of relay 1 comprises the primary winding 7 of transformer 6 and the source of space current B connected in series and arranged in the circuit as shown. The magnetic circuit of transformer 6 preferably comprises magnetic material al-

though a transformer of the air core type may be employed.

The control electrode-cathode circuit of relay 8 comprises the secondary winding 9 of transformer 6 and inductance device 10 connected in series with each other and arranged in the circuit as shown. The inductance 10 is preferably of the air core type and serves to neutralize the capacity effects of the relay 8 to thereby prevent the establishment of undesirable oscillations.

A condenser 11 may be connected across the winding 9 for tuning the control electrode-cathode circuit to the desired frequency. A variable condenser 12 is connected between points on the windings 7 and 9. The degree of amplification together with the quality of amplification is found to be greatly improved by this arrangement.

The anode-cathode circuit of relay 8 comprises the primary winding 13 of transformer 14 and the source of space current B connected in series with each other and arranged in the circuit as shown. A variable condenser 15 may be connected in this circuit, as shown, for tuning it to the desired frequency.

The control electrode-cathode circuit of relay 15 comprises an inductance 16 and the secondary winding 17 of transformer 14 connected in series with each other and arranged in the circuit as shown. A variable condenser 18 is connected in shunt with the inductance 16 for effecting an increase in the impedance of the combination with an increase in signal frequency to thereby prevent the establishment of undesirable oscillations.

A variable condenser 19 may be connected across the winding 17 for tuning the circuit to the desired frequency. I have found by experiment that the connection of a condenser 20 between points on the windings 13 and 17 increases the degree and quality of amplification; the condenser 20 may be equal in magnitude or less than that of the tuning condensers such as 15 or 19. I have also ascertained by experiment that the use of such a condenser renders unnecessary the serious consideration of the capacity between the windings 13 and 17 thereby resulting in a

simple and inexpensive transformer. I have not as yet arrived at a satisfactory theoretical explanation of this and I reserve the right to insert this explanation at a later date if I so desire.

5 The anode-cathode circuit of relay 45 comprises the primary winding 21 of transformer 22 and the source of space current B connected in series with each other and 10 arranged in the circuit as shown. A condenser 23 may be connected across the winding 21 for tuning the circuit to the desired frequency.

15 The control electrode-cathode circuit of relay 24 comprises a resistance 25 and the secondary winding 26 of transformer 22 connected in series with each other and arranged in the circuit as shown. A shunt comprising an inductance 27 and a condenser 28 connected in series with each other is connected across points of said resistance, one of said points being variable, as shown. As the signal frequency increases this shunt forces more current through the resistance 25 and 20 thereby increases the resistance to the establishment of undesirable oscillations. A condenser 29 may be connected across the winding 26 for tuning the circuit to the desired frequency. A condenser 30 is also preferably connected across points on windings 21 and 26 as shown. The anode-cathode circuit of relay 24 may be appropriately connected to some other device such as a detector, etc.

25 35 All of the variable tuning elements may be simultaneously controlled by a single control means or they may be controlled in various groups.

40 While I have shown and described a preferred embodiment of my invention, I do not limit myself to the same; but may employ such other modifications as come within the spirit and scope of my invention.

I claim:

45 1. In a wave signaling system, a vacuum tube having a grid, a plate and a filament, a tunable circuit comprising an inductance and a variable condenser in parallel, said filament being connected to one terminal of 50 said condenser, a resistance connected between the other terminal of said condenser and said grid, said resistance being not included in said tunable circuit, and a shunt path across the terminals of said resistance, 55 said shunt path comprising an inductance and a condenser in series.

60 2. In a signaling system, the combination with a thermionic tube including anode, cathode and grid, of input and output circuits associated with said cathode and grid and said cathode and anode respectively, whereby there exists a tendency for the setting up of undesired oscillations in said tube, and means for preventing such undesired oscillations, comprising in series with said

input circuit and said tube an inductance shunted by a capacity.

65 3. In a signaling system, the combination with a thermionic tube including anode, cathode and grid, of an input circuit connected between said grid and cathode and an output circuit connected between said cathode and anode respectively, whereby there exists a tendency for the setting up of undesired oscillations in said tube, and means serially interposed between said input circuit and said grid for preventing such oscillations, said means comprising an inductance shunted by a capacity.

70 4. In a signaling system, the combination with a thermionic tube including anode, cathode and grid, of input and output circuits associated with said cathode and grid, and said cathode and anode respectively, whereby there exists a tendency, increasing with frequency, for the setting up of undesired oscillations in the said tube, and means in series with said input circuit for preventing such oscillations, comprising inductive reactance shunted by an impedance such that the resultant impedance of said means increases with frequency at a rate sufficient to offset the increased tendency at the higher frequencies for the setting up of such oscillations.

75 5. In a signaling system, the combination with a thermionic tube including anode, cathode and grid, of input and output circuits associated with said cathode and grid and said cathode and anode respectively, whereby there exists a tendency, increasing with frequency, for the setting up of undesired oscillations in the said tube, and means in series with said input circuit for preventing such oscillations, comprising an inductance shunted by a capacity such that the resultant impedance of said means increases with frequency at a rate sufficient to offset the increased tendency at the higher frequencies for the setting up of such oscillations.

80 100 6. In a signaling system, a thermionic tube provided with a filament, a grid and a plate, an input circuit for said thermionic tube including the secondary winding of a transformer having a capacity connected in multiple therewith, said input circuit including said grid and said filament, an inductance unit in series with said input circuit and an impedance unit in shunt with said inductance unit whereby the impedance of said input circuit increases with frequency in order to prevent oscillations, and an output circuit for said thermionic tube including said filament and said plate.

105 115 120 125 7. In a signaling system, a thermionic tube provided with a filament, a grid and a plate, an input circuit for said thermionic tube including the secondary winding of a transformer and a capacity connected in multiple,

5 said input circuit including said grid and filament, an inductance unit in series with said input circuit and a capacity unit in shunt with said inductance whereby the impedance of said input circuit increases with 70 frequency in order to prevent undesired oscillations, and an output circuit for said thermionic tube.

10 8. In a signaling system, the combination with a thermionic tube including anode, cathode and grid, of input and output circuits associated with said cathode and grid and said cathode and anode respectively, whereby there exists a tendency, increasing 75 with frequency, for the setting up of undesired oscillations in said tube, and means for preventing such oscillations, comprising a resistance in series with said input circuit and said tube, and an impedance including inductance connected in shunt with said resistance, said resistance and impedance being so proportioned that the resultant impedance of said means increases with frequency at a rate sufficient to offset the increased tendency 80 at the higher frequencies for the setting up of such undesired oscillations.

15 9. In a signaling system, the combination with a thermionic tube including anode, cathode and grid, of input and output circuits associated with said cathode and grid and said cathode and anode respectively, whereby there exists a tendency, increasing 85 with frequency, for the setting up of undesired oscillations in said tube, and means for preventing such oscillations, comprising a resistance in series with said input circuit and said tube, and an impedance including inductance and capacity connected in shunt with said resistance, said resistance and impedance being so proportioned that the resultant impedance of said means increases with frequency at a rate sufficient to offset the increased tendency at the higher frequencies for the setting up of such undesired oscillations. 100

20 10. In a signaling system, the combination with a thermionic tube including anode, cathode and grid, of input and output circuits associated with said cathode and grid and said cathode and anode respectively, whereby there exists a tendency, increasing 105 with frequency, for the setting up of undesired oscillations in said tube, and means for preventing such oscillations, comprising a resistance in series with said input circuit and said tube, and an impedance in shunt with said resistance, said impedance including capacity and inductance in series, and said resistance and impedance being so proportioned 110 that the resultant impedance of said means increases with frequency at a rate sufficient to offset the increased tendency at the higher frequencies for the setting up of such undesired oscillations.

25 11. In a signaling system, the combination

with a thermionic tube having anode, cathode and grid, of input and output circuits associated with said cathode and grid and said cathode and anode respectively, whereby there exists a tendency for the setting up 70 of undesired oscillations in said tube, and means for preventing such oscillations comprising, a resistance in series with said input circuit and said tube, and an impedance variably shunting said resistance, said impedance 75 including capacity and inductance in series.

12. In a wave signaling system, a vacuum tube having a grid, a plate and a filament, a tunable circuit comprising an inductance and a variable condenser in parallel, said filament 80 being connected to one terminal of said condenser, a resistance connected between the other terminal of said condenser and said grid, said resistance being not included in said tunable circuit, and an impedance variably shunting said resistance, said impedance 85 comprising an inductance and a capacity in series.

13. In a signaling system, the combination with a thermionic tube including anode, 90 cathode and grid, of an input circuit connected between said grid and cathode and an output circuit connected between said cathode and anode, respectively, whereby there exists a tendency for the setting up of undesired oscillations in said tube, and means serially interposed between said input circuit and said grid for preventing such oscillations, said means comprising a resistance variably 95 shunted by inductance and capacity in series. 100

14. In a signaling system, the combination with a thermionic tube including anode, cathode and grid, of input and output circuits associated with said cathode and grid and said cathode and anode, respectively, whereby there exists a tendency for the setting up 105 of undesired oscillations in said tube, and means in series with said input circuit and said tube for preventing such oscillations comprising resistance variably shunted by 110 capacity and inductance in series such that the resultant impedance of said means increases with frequency at a rate sufficient to offset the increased tendency for the setting up of such undesired oscillations at the higher 115 frequencies.

15. In a radio frequency amplifying system, the combination with a thermionic tube including anode, cathode and grid, of input and output circuits associated with said cathode and grid and said cathode and anode respectively, whereby there exists a tendency, increasing 120 with frequency, for the setting up of undesired oscillations in said tube, and means for preventing such oscillations, comprising a resistance in series with said input circuit, and an impedance including capacity in shunt with said resistance, said resistance and impedance being so proportioned that the resultant impedance of said means in- 125

creases with frequency at a rate sufficient to offset the increased tendency at the higher frequencies for the setting up of such undesired oscillations.

- 5 16. A signal receiving system including a plurality of electron tubes each having grid, filament and plate electrodes, input and output circuits interconnecting said electrodes with the output circuit of one electron tube
10 interlinked with the input circuit of a succeeding electron tube, and a pair of parallel branch circuits connected in the input circuit of one of said electron tubes, an inductance and capacity in series in one branch thereof and resistance in the other branch thereof, said circuits having an effective resistance variable at a predetermined rate in proportion to the selected signaling frequency for preventing the flow back of undesired
15 oscillatory currents while permitting the free transfer of signaling energy of a selected frequency through said plurality of electron tubes.
20 17. A signal receiving system including a plurality of electron tubes each having grid, filament and plate electrodes, input and output circuits interconnecting said electrodes with the output circuit of one electron tube interlinked with the input circuit of a succeeding electron tube, and a pair of parallel branch circuits connected in the input circuits of said electron tubes, said parallel branch circuits having an effective resistance variable at a predetermined rate in accordance with changes in frequency and operating to prevent the flow back of undesired oscillatory current in said circuits while permitting the free transfer of signaling energy of a selected frequency characteristic.
